LASTING MACHINE

Lloyd G. Miller, Beverly, Mass., assignor to United
Shoe Machinery Corporation, Flemington, N. J.,
a corporation of New Jersey

Application November 4, 1942, Serial No. 464,470

82 Claims. (Cl. 12—14)

This invention relates to lasting machines, and is herein illustrated as applied to a machine of the same general character as disclosed in United States Letters Patent No. 2,075,852, granted on April 6, 1937, on an application of B. Jorgensen's, but modified in certain respects as further disclosed in Letters Patent No. 2,339,504, granted on January 18, 1944, on an application of mine. It is to be understood, however, that the invention is not thus limited in its applicability.

A particular object of the invention is to provide, in addition to toe-lasting means, means for lasting in a speedy and efficient manner the sides of the forepart of a shoe beyond its toe-end portion. A further object is to provide side-lasting means so constructed as to adapt it to be readily applied to prior machines such, for example, as disclosed in the above-mentioned Letters Patent with but little change in the structure of such machines. To these and other ends, the machine herein shown has, in addition to toe wipers which wipe the margin of an upper inwardly over an insole on a last around the toe end of the last, side wipers which are swung inwardly about axes extending heightwise of the last to wipe the margin of the upper over the insole at the sides of the forepart beyond the toe wipers and toward which the toe wipers are movable lengthwise of the shoe, the construction shown being further such that the side wipers have components of movement lengthwise of the shoe toward the toe wipers during the greater portion of the wiping operation and are moved lengthwise of the shoe in the same direction as the toe wipers near the end of that operation after the toe wipers have arrived substantially in positions to engage them. In this manner the margin of the upper at the sides of the forepart is wiped inwardly in directions such as to obtain the best results, especially in operating on the ball portion of the shoe where the edges of the shoe bottom are inwardly curved rearwardly of the ball line, and insurance is afforded also that portions of the margin of the upper at the junction of the toe wipers and the side wipers will be smoothly wiped down on the insole. As further herein illustrated, the side wipers are operated by members which by turning movements about axes extending heightwise of the shoe serve as heretofore to close the toe wipers inwardly widthwise of the shoe, the side wipers being mounted on wiper carriers which are pivotally connected to these members and which have thereon cam faces engaged by appropriate means to determine the paths of movement of the carriers and the wipers.

In a further aspect, the invention has especially in view such control of the margin of an upper as to insure that it will be lasted tightly over an insole without danger of adhering prematurely thereto in lasting with cement, and also such control of the margin of the insole as to insure that it will be properly positioned on the bottom of the last when the margin of the upper is lasted inwardly over it. For the accomplishment of these and other objects the machine herein shown, which in common with prior machines of the same general type has a presser foot carrier movable to carry a presser foot into engagement with the forepart of the insole and to cause the presser foot to move the shoe heightwise relatively to the toe-lasting means, is provided with members supported by the presser foot carrier for controlling the margin of the insole adjacent to the side wipers and for pressing the margin of the upper against these wipers as they are moved inwardly over the insole. As illustrated, these members are movable outwardly over the insole toward its side edges in response to engagement of the insole therewith, thus insuring that the margin of the upper will be spread from over the insole, and are movable thereafter inwardly over the insole by the side wipers. To facilitate such movements of the members, they are pivotally supported on arms relatively to which they are thus outwardly movable and which move with them against the resistance of springs as the members are forced inwardly over the insole. In one form of construction disclosed outward return movements of the members when the wipers are retracted from over the shoe are prevented by latch mechanism controlling these arms, the arms being released by means actuated by engagement with the insole of the next shoe. To insure against damaging or displacing the margin of the insole, especially if the bottom of the forepart of the last has a pronounced lateral curvature, the construction shown is further such that the pressure of the above-mentioned members on the insole is relieved as they start to move inwardly, means being provided for lifting them by the action of the wipers as the latter are deflected heightwise of the last by the upper at the extreme edge of the insole. Through this means also, if the above-mentioned latch mechanism is not used, the members are maintained far enough from the insole to avoid displacing the margin of the upper when they move outwardly with the wipers. Still another advantageous characteristic of the embodiment of the invention herein disclosed is

that the insole-engaging and upper-controlling members serve also to insure that the shoe is positioned in proper relation to the wipers with respect to tipping movement about a longitudinal axis.

The above and other features of the invention, including various novel details of construction and combinations of parts, will now be more particularly described with reference to the accompanying drawings and thereafter pointed out in the claims.

In the drawings,

Fig. 1 is a view partly in front elevation and partly in section of the upper portion of a machine in which the invention is embodied, the parts being shown in the positions which they occupy shortly after the starting of the power operation of the machine;

Fig. 2 shows mainly the insole and upper controlling mechanism as viewed in the direction of the arrow A in Fig. 1, with the parts in the same positions as in Fig. 1;

Fig. 3 is a plan view showing the wipers and their operating mechanisms, portions of a cover plate over the wipers being broken away;

Fig. 4 is a view in end elevation of the left-hand side wiper shown in Fig. 1 and of parts associated therewith, the cover plate being shown in section;

Fig. 5 is a section on the line V—V of Fig. 3;

Fig. 6 is a view similar to Fig. 3, but showing the parts in the positions which they occupy at the end of the inward wiping movements of the wipers;

Figs. 7, 8 and 9 are views similar to Fig. 2, but showing the parts in different positions which they assume in the course of the lasting operation;

Fig. 10 is a view in front elevation of an alternative construction whereby the insole and upper controlling members are controlled somewhat differently than in the construction shown in Figs. 1 and 2;

Fig. 11 is a view similar to Fig. 2, showing the alternative construction and also showing the parts as they appear slightly earlier in the operation of the machine than in Fig. 2;

Fig. 12 is a section on the line XII—XII of Fig. 11; and

Fig. 13 is a view similar to Fig. 7, showing the alternative construction and showing the parts as they appear at the same time in the operation of the machine as in Fig. 7.

In view of the disclosures in the previously mentioned Letters Patent, only such parts of the machine as it is necessary to refer to for an understanding of the invention will be herein described. The shoe and its last are supported in position for the lasting operation on a toe rest 2 and on a heel-end support 4 which includes a last pin 6 arranged to enter the usual spindle hole in the heel end of the last. For lasting the toe end of the shoe the machine is provided with means including a gripper 8 which grips the margin of the upper around the toe end of the last and pulls the upper heightwise of the last in response to downward movement of the shoe and last, the gripper being closed on the upper by the operator prior to the starting of the power operation of the machine. In response to such downward movement of the shoe and last the upper is also wiped heightwise of the last around the toe end and along portions of the sides of the forepart beyond the toe end by a flexible toe former 10. Thereafter the margin of the toe end

of the upper is wiped inwardly over an insole on the last into position to be secured to the insole by cement by means of toe wipers 12, the gripper 8 being opened automatically to release the upper. The downward movement of the shoe is effected by an insole-engaging presser foot 14 carried by an arm 16 which is swung forwardly by the operator to bring the presser foot to a position over the forepart of the insole and is then moved downwardly in the power operation of the machine. The presser foot 14 is supported on a bracket 18 adjustable by a screw 20 relatively to the arm 16 in directions heightwise of the shoe to vary the limit of downward movement of the shoe. Also carried by the arm 16 is a member 22 which engages the toe end of the insole and is forced upwardly away from the insole by pressure of the margin of the upper against it as the upper is wiped inwardly by the toe wipers 12. As the shoe is moved downwardly by the presser foot 14 the toe rest 12 moves with it against the resistance of a spring 24, and in response to the downward movement of the toe rest downward movement of equal extent is imparted also to the heel-end support 4 against the resistance of a spring 26, as more particularly disclosed in Letters Patent No. 2,339,504. As also therein disclosed, the heel-end support 4 is provided with a heel rest 28 which is swung lengthwise of the shoe from the initial idle position in which it is shown in Fig. 1 into engagement with the heel-end face of the shoe by pressure of the top face of the heel end of the last on one arm of a lever 30 supporting the heel rest, this movement of the heel rest taking place in response to pressure on the bottom of the forepart of the shoe prior to the downward movement of the shoe as a whole, as more particularly hereinafter explained.

The wipers 12 are operated by mechanism constructed substantially as disclosed in the previously mentioned Letters Patent No. 2,075,852, but they do not extend so far lengthwise of the shoe as heretofore and are accordingly limited substantially to engagement with the toe-end portion of the upper. They are advanced bodily lengthwise of the shoe by a wiper carrier 32 on which they are supported, the carrier being movable along guideways on a toe head 34 and being operated by a gear sector 36 fast on a rock-shaft 38 and engaging teeth on the lower face of the carrier. For swinging or closing the wipers laterally of the shoe about a common axis at the end of the toe there are provided, as further disclosed in the last-mentioned Letters Patent, rack bars 40 operated by the rockshaft 38 and connected by screws 42 to slides 44 mounted in guideways in the toe head 34. Each slide 44 is connected by a link 46 to a member 48 mounted to turn about an eccentric 50 positioned on a stud 52 on the toe head. Each member 48 is connected to the wiper 12 associated therewith by a link 54 mounted at one end on a stud 56 on the member 48 and at its other end on a stud 58 on the wiper. It will thus be seen that as the wipers are advanced lengthwise of the shoe by the wiper carrier 32 they are closed inward laterally of the shoe by turning movements of the members 48 about the eccentrics 50, the members 48 being thus turned by the movements of the slides 44 and acting on the wipers through the links 54. In the earlier construction shown in Letters Patent No. 2,075,852 the eccentrics corresponding to those herein designated as 50 were turned to vary the starting positions of the wipers in response to lateral shifting movement of the toe

former 10 to different positions determined respectively by right and left shoes as the latter were moved downward relatively to the toe former, after which the eccentrics were locked to prevent them from being displaced during the wiping movements of the wipers. In the machine herein shown, however, the necessity for thus adjusting the wipers for right and left shoes does not arise by reason of the fact that provision is afforded in the construction of the heel-end support 4, as more fully disclosed in Letters Patent No. 2,339,504, for bodily displacement of the heel ends of right and left shoes, along with the last pin 6, to different laterally offset positions respectively, so that the longitudinal median line of the forepart of each shoe is in substantially the same relation to the toe wipers whether the shoe be a right shoe or a left shoe. Accordingly, each eccentric 50 is locked permanently against turning movement about the stud 52 by a pin 60 mounted on the toe head and located in a slot formed in an extension 62 of the eccentric. The wipers 12 are, as heretofore, maintained in a heated condition to render them more effective in wiping the upper smoothly over the insole, the heating means in the construction shown comprising an electrical heating unit 64 embedded in a cover plate 66 fast on the toe head 34 over the wipers, heat being conducted from the cover plate to the wipers partly through the links 54 which are movable in contact with the cover plate and are enlarged lengthwise of the shoe to provide extended surfaces thus engaged by the cover plate.

For purposes of this invention, the machine shown is further provided with side wipers, identified generally by the reference character 68, arranged to wipe the margin of the upper inwardly over the insole into position to be secured thereto by cement along the opposite sides of the shoe from the toe-end portion heelwardly as far as the beginning of the shank portion of the shoe, so that if the shoe has already been lasted along its shank portion, as will be the usual condition when a shoe is presented to the machine, no further side lasting will be required after the shoe leaves the machine. Each side wiper 68 includes a wiper plate 70 a portion only of which, located next to the toe portion of the shoe, is arranged to engage the upper, and another wiper plate 72 extending heelwardly from the upper-engaging portion of the plate 70, the plate 72 being resiliently flexible in directions heightwise of the shoe and secured at one end to the plate 70 in a recess in the latter by means of rivets 74 (Fig. 3). The top face of the opposite end portion of the plate 72 is engaged by two screws 76 which are threaded in the plate 70 for adjusting the plate 72 to conform better to the contour of the bottom of the ball portion of the shoe. The plate 70 is secured by screws 78 to a wiper holder 80 which is fast on a pin 82 (Fig. 4) extending lengthwise of the shoe and mounted for turning movements in a block 84 secured by screws 86 to one end of a wiper carrier 88. The wiper 68, including the plates 70 and 72, is, therefore, mounted to swing with the holder 80 in directions heightwise of the shoe about the axis of the pin 82 between limits determined respectively by engagement of a shoulder 90 (Fig. 4) on the wiper holder with the wiper carrier 88 and by engagement of the holder with a screw 92 threaded in the block 84. A plunger 94 mounted in the block 84 and controlled by a spring 96 tends by engagement with

the plate 70 to swing the wiper holder 80 downwardly, and against the resistance of this spring the wiper 68 and the holder are arranged to be deflected upwardly by engagement of the upper 5 with the wiper at the edge of the insole as the wiper begins its wiping action on the upper, the upper-engaging faces of the inner marginal portions of the plates 70 and 72 being upwardly inclined to render the upper thus effective thereon, as illustrated in Figs. 2 and 4.

Each of the side wiper carriers 88 is supported underneath on the toe head 34 and is pivotally connected by a pin 98, at the end thereof remote from the side wiper 68, to the member 48 15 previously referred to as movable about the eccentric 50 for closing the corresponding toe wiper 12. The turning movement of the member 48 accordingly serves also to operate the side wiper carrier 88 and thus to impart operative movement to the side wiper 68, the carrier being bodily movable by force applied thereto by the member 48 and directed generally lengthwise of the shoe. The wiper carrier 88 is provided with a cam face 100 arranged to be engaged by a roll 102 mounted on a stud 104 which is fast on the cover plate 66 to determine the path of movement of the carrier and the side wiper and to cause the wiper to be moved inwardly widthwise of the shoe. The operative inward movement 20 of each side wiper is effected against the resistance of a spring 106 connected at one end to the toe head 34 and at the other end to a screw 108 in the block 84. It will be evident that the spring tends to swing the wiper carrier outwardly 25 widthwise of the shoe and holds it at all times against the roll 102. In its inward movement the wiper swings with the wiper carrier about the pin 98 located opposite the side of the toe with a component of movement lengthwise of 30 the shoe toward the toe end thereof, as indicated diagrammatically in Fig. 3 by broken lines indicating different successive positions of one end of the wiper plate 70. It will be noted that initially the toe wipers 12 are spaced substantial 35 distances lengthwise of the shoe from the side wipers 68, and the movements of the toe wipers lengthwise of the shoe as they are advanced and closed inwardly over the shoe bottom cause them to meet the side wipers near the end of the wiping operation, the ends of the toe wipers being convexly curved at 110 and the side wiper plates 70 being complementally curved at 112 to fit the curves 110 when the toe wipers and the side wipers meet. The contours of the cam faces 100 40 on the side wiper carriers 88 are further such that just before the end of the operative movements of the several wipers the side wipers have components of movement in a heelward direction with the toe wipers, as also illustrated diagrammatically in Fig. 3, which insures that the portions of the margin of the upper at the junction of the toe wipers and the side wipers will be smoothly wiped down on the insole. The side wipers as well as the toe wipers are maintained in a heated condition by the cover plate 66 with which the blocks 84 are substantially in contact, heat being conducted to the side wipers partly through these blocks and the wiper holders 80. Heat also is conducted to the side wipers through the links 54 which are received in recesses 114 in the wiper plates 70 as the wipers are operated.

Associated respectively with the different side wipers 68 are devices 116 (Fig. 2) having the function of what are commonly known in the art

as retarders and which may be so termed, these devices being arranged to clamp or press the marginal portion of the upper against the edges of the wipers as the latter are moved inwardly over the insole to render the wipers more effective to wipe the upper tightly and smoothly over the insole. The retarders 116 also prevent the margin of the upper from adhering prematurely to the insole, and in the construction herein shown serve additionally to press the margin of the insole down on the bottom of the last before the wipers begin to wipe the upper inwardly over it. The retarders are supported by the bracket 18 previously referred to as carried by the downwardly movable arm 16 and on which the presser foot 14 also is supported. For thus supporting the retarders a rod 118 extends lengthwise of the shoe from the bracket 18, and mounted on this rod for swinging movements laterally of the shoe are two downwardly extending arms 120, one for each of the retarders. Torsion springs 122 (Fig. 1) connected respectively to the two arms 120 tend to swing them outwardly and hold them initially in positions determined by a rod 124 extending from the bracket 18 through slots 126 in the arms and engaged by stop screws 128 threaded in the arms. Pivotaly mounted by means of pins 130 in vertical slots in the lower ends of the arms 120 are levers 132 which directly support the retarders 116, each retarder comprising an insole-engaging and upper-clamping member 134 fastened by a screw 136 to a downwardly extending arm of the lever 132 and so formed as to extend a substantial distance lengthwise of the shoe along the ball portion thereof. The relation of each member 134 to the axis of its supporting lever 132 is such that the member may swing relatively to the arm 120 in directions widthwise of the shoe with components of movement also heightwise of the shoe. Mounted in a socket in each arm 120 is a light spring 138 bearing at its lower end on a plunger 140 which engages the lever 132 mounted on that arm and tends to swing the lever in one direction relatively to the arm, the limit of such swinging movement of the lever being adjustably determined by engagement with the arm of a screw 142 threaded in an upwardly extending portion of the lever. By the springs 138, therefore, the members 134 are normally held in retracted positions at a distance from each other considerably less than the width of the forepart of the insole of the shoe over which they are to operate, and in response to engagement of the insole with these members upon downward movement of the arm 16 they are swung outwardly against the resistance of the springs 138 into positions to clamp the marginal portion of the upper against the wipers first substantially at the edge of the insole when the wipers are thereafter moved inwardly (Fig. 7). Since the members 134 are pressed downwardly on the insole through the springs 138 they position the margin of the insole properly on the bottom of the last before the upper is wiped inwardly over it. It will be understood that when the members 134 are thus positioned adjacent to the edge of the insole the arms 120 which support them and their levers 132 are maintained by the springs 122 in their outer positions determined by the pin 124 and the screws 128, and by adjusting these screws the positions to which the members 134 are moved may be varied as required by shoes of different widths. As the wipers 68 are moved inwardly over the insole they force the members 134 also inwardly by pressure against them, the

margin of the upper being withdrawn from between these members and the wipers as the wiping operation progresses. In this operation, however, the members 134 are not swung inwardly about the axes of the pins 130, but about the axis of the rod 118 which is located considerably farther from the insole than the pins 130, each member 134 and its supporting arm 120 being moved as a unit about this axis against the resistance of the spring 122 which controls that arm. To bring this about each member 134 has integral therewith an arm 144 arranged to extend outwardly over the corresponding wiper 68 and the wiper holder 80 associated therewith and provided with a screw 146 the lower end of which is arranged to be engaged by the top face of a block 148 formed integral with the wiper holder. It will be evident that by reason of the engagement of this block with the screw the member 134 and the lever 132 on which it is mounted are prevented from swinging in an inward direction over the insole about the axis of the corresponding pin 130, and accordingly the pressure of the wiper against the member 134 causes the corresponding arm 120 to swing against the resistance of its controlling spring 122. It is through the force of this spring, therefore, that the upper is pressed against the wiper by the member 134.

When the retarder members 134 are moved inwardly over the insole as above described, it is desirable, in order to avoid any possibility of damage to the insole or of displacement of its margin if it is a thin insole, to relieve the pressure of the members on the insole, especially if the bottom of the forepart of the last has a pronounced lateral curvature. In the construction herein shown this object is accomplished by action of the blocks 148 on the screws 146. As hereinabove explained, the wipers 68, as they begin to act on the upper, are deflected upwardly by the engagement of the upper therewith at the edge of the insole, both the wipers and their holders 80 swinging upwardly about the axes of the pins 82. Such upward movement of the wipers causes the blocks 148 on the wiper holders, by their engagement with the screws 146, to move the members 134 also upwardly (Fig. 8). The amount of movement thus imparted to the members 134 may be varied by adjustment of the screws 146. Preferably, as herein illustrated, the amount of movement of the members is such as to disengage them from the insole, since their holdown function is no longer needed after the wipers have begun to press the upper against the insole. It will be understood that such lifting of the members 134 is permitted by the pivotal connections between their supporting levers 132 and the arms 120 and the provision for yielding movements of these arms against the resistance of the springs 122. After the members 134 have thus been lifted they are still maintained in positions to clamp the marginal portion of the upper against the wipers until the upper is withdrawn from between them and the wipers near the end of the overwiping operation.

Machines such as that to which the invention is herein illustrated as applied have been provided heretofore with a device carried by the arm 16 for engaging the bottom of the forepart of the shoe at its opposite sides and for tipping the shoe laterally to position it in proper relation to the toe wipers if it is not already in that relation. Such a device is that identified by the reference character 382 in the previously mentioned Letters Patent No. 2,075,852. In the construction

herein shown the same function is performed by the retarder members 134 in addition to their other functions. That is, by the pressure of these two members on the insole under the influence of the springs 138, the proper position of the shoe with respect to movement about an axis extending lengthwise thereof is determined, the shoe, if necessary, being tipped laterally by one or the other of these members until they both press with substantially equal forces on the insole. It will be understood that as this operation takes place the presser foot 14 is still somewhat above the insole, the presser foot arriving in insole-engaging position just as the members 134 in their outward movements arrive in proper positions for thereafter clamping the marginal portion of the upper against the side wipers. The members 134, by their pressure on the bottom of the forepart of the shoe, also assist in tipping the shoe about the toe rest 2 in such manner as to force the heel end of the last downwardly on the last pin 6 and thus to apply the heel rest 28 to the shoe through the pressure of the last on the lever 30 in the manner more fully disclosed in the previously mentioned Letters Patent No. 2,339,504, additional pressure for this purpose being applied to the forepart of the shoe by the presser foot 14 immediately prior to the bodily downward movement of the shoe effected by the presser foot.

The manner of operation of the machine constructed as thus far described, in so far as it is of interest with reference to the present invention, will now be briefly summarized. The operator presents a shoe to the machine in the same manner as heretofore, inserting the margin of the toe end of the upper in the toe gripper 8 and then closing this gripper on the upper by the means provided for that purpose. When the shoe is thus presented the heel end of the last rests on one arm of the lever 30 with the upper end only of the last pin 6 extending loosely into the spindle hole in the last, as shown in Fig. 1. The operator then swings the arm 16 forwardly toward him to carry the presser foot 14, the member 22 and the retarder members 134 to positions over the bottom of the forepart of the shoe, and as a result of such movement of the arm 16 the machine is started in operation as heretofore. Immediately after the starting of the machine downward movement is imparted to the arm 16, and the retarder members 134 are carried by the arm into positions to engage the bottom of the forepart of the insole as illustrated in Figs. 1 and 2, these figures showing the parts as they appear just as these members arrive in insole-engaging positions. Further downward movement of the arm 16 causes the members 134 to be moved outwardly over the insole toward the opposite side wipers 68 in response to the pressure of the insole thereon, until these members are in such positions as to press the marginal portion of the upper against the side wipers substantially over the opposite side edges of the insole when the wipers are thereafter moved inwardly. In thus moving outwardly over the insole the members 134 and the levers 132 on which they are mounted swing relatively to the arms 120 about the axes of the respective pins 130 against the resistance of the springs 138, these movements terminating upon engagement of the presser foot 14 with the insole. As the members thus engage the insole and receive their outward movements they serve to position the shoe in proper relation to the wipers, if it is not already in that relation, by tipping it laterally in one

direction or the other until the pressures of the two members on the insole are substantially equalized. The members 134 and the presser foot 14, by their pressure on the bottom of the forepart of the shoe, also cooperate to tip the shoe about the toe rest 2 in the direction to force its heel end downwardly and thus to cause the heel rest 28 to be applied to the heel-end face of the shoe by the action of the last on the lever 30. Thereafter further downward movement of the arm 16 serves to impart bodily downward movement to the shoe, together with the toe rest 2 and the heel-end support 4, causing the toe end of the upper to be pulled by the gripper 8 and rendering the toe former 10 effective to wipe the upper heightwise of the last.

After the downward movement of the shoe the toe and side wipers are operated in the manner hereinbefore described to wipe the margin of the upper inwardly over the insole into position to adhere to the insole around the toe end and along the sides of the forepart as far rearwardly as the beginning of the shank portion of the shoe. In this operation the toe wipers 12, which are initially spaced substantial distances lengthwise of the shoe from the side wipers 68 as illustrated in Fig. 3, are advanced and closed inwardly over the shoe lengthwise and laterally thereof, and the side wipers are swung inwardly with components of movement lengthwise of the shoe toward the toe wipers, as indicated diagrammatically in Fig. 3. Just before the end of the inward wiping movements of the several wipers the toe wipers and the side wipers meet, the convex edges 110 of the toe wipers engaging the concave edges 112 of the side wiper plates 70, and thereafter, as the toe wipers complete their advancing and closing movements, the side wipers move with them a short distance lengthwise of the shoe, thus insuring that the upper at the junction of the toe wipers and side wipers will be smoothly wiped down on the insole. The positions of the several wipers at the end of their wiping movements are illustrated in Fig. 6.

When the wipers are operated as above described, the member 22 serves as heretofore as a holdown for the toe-end portion of the insole and as a retarder for clamping the margin of the toe end of the upper against the wipers 12 until the margin of the upper is wiped inwardly under it by the wipers, and the members 134 serve first as holdowns for the opposite side margins of the insole and thereafter as retarders to control portions of the upper wiped inwardly by the side wipers. It will be evident that when the members 134 are moved outwardly over the insole as above described the screws 146 are swung to such positions as to receive under them the blocks 148 formed on the wiper holders 80 when the side wipers are moved inwardly toward the edge of the insole. When these wipers first engage the upper the lower faces of their plates 70 and 72 are positioned somewhat lower than the bottom face of the insole, as illustrated in Fig. 7, or at all events in such relation to the shoe as to require the wipers to be deflected somewhat upwardly by the contact of the upper with their inner inclined edge portions in order to permit them to wipe the upper inwardly over the bottom face of the insole. Such upward deflection of the wipers is accompanied by upward swinging movements of the wiper holders 80 about the axes of the pins 82 against the resistance of the springs 96, and by reason of the engagement 75 of the blocks 148 with the screws 146 the retarder

members 134 are at the same time lifted to relieve their pressure on the insole and preferably to space them somewhat above the insole, as illustrated in Fig. 8. This serves to avoid any danger of damage to the insole or of displacement of its marginal portions by the members 134 as the wipers are moved farther inwardly and force these members inwardly with them. It will be evident that while the members 134 may thus be lifted far enough to space them from the insole, they are still maintained in positions to clamp the marginal portion of the upper against the side wipers and to control it until it is withdrawn from between them and the wipers. As the members 134 are forced inwardly over the insole by the wipers, they are prevented from swinging inwardly about the axes of the pins 130 by the contact of the blocks 148 with the screws 146, and accordingly the arms 120, which support the levers 132, are forced to swing about the rod 118 against the resistance of their controlling springs 122, as shown in Fig. 9.

In a machine such as that to which the invention is herein shown as applied the arm 16 receives a slight upward movement to permit the shoe to be pressed more forcibly against the wipers by the toe rest 2 after the wipers have completed their wiping movements, and the machine then comes to a stop with the heated wipers in pressure-applying engagement with the upper to allow more time for the cement to set. After a few seconds the machine is again started automatically, whereupon the arm 16 is moved downwardly enough to relieve somewhat the pressure of the wipers on the shoe and the wipers are then retracted from over the shoe bottom. As the side wipers are thus retracted, the arms 120 are swung reversely toward their starting positions by the springs 122. Ordinarily the retarder members 134 continue at this time to be controlled by the engagement of the blocks 148 with the screws 146, so that they are prevented from being swung downwardly by the springs 138 and are held far enough above the insole to clear satisfactorily the overwiped margin of the upper while moving outwardly with the side wipers. In order, however, to afford still greater insurance against displacement of the margin of the upper by the members 134 under any conditions, the construction shown in Figs. 10 to 13 inclusive may be utilized. In this construction there is pivotally mounted by means of a pin 150 on the hub of one of the arms 120 a latch 152 arranged to engage a pin 154 on the hub of the other arm 120 to retain these arms in the positions to which they are moved by the pressure of the side wipers on the retarder members 134 and thus to prevent these members from being moved outwardly toward the edge of the insole when the wipers are retracted. A spring-pressed plunger 156 mounted in that arm 120 which carries the latch 152 acts on a tail portion of the latch to swing the latch automatically into holding relation to the pin 154 when the wipers arrive substantially at the limits of their inward wiping movements. At this time the retarder members are in the same relative positions as illustrated in Fig. 9 with reference to the previously described construction, and it will be understood that as the wipers are retracted the blocks 148 move out from under the screws 146, thus permitting the members 134 to be swung still farther inwardly toward each other by the action of the springs 138 on the levers 132, the members finally assuming positions as near to-

gether as illustrated in Fig. 11 when the arm 16 is lifted. In the operation of the machine on the next shoe the latch 152 is swung upwardly to release the arms 120 upon downward movement of the arm 16. For this purpose there is mounted for vertical movements in the bracket 18 a slide 158 extending downwardly from which is a pin 160 arranged to engage the insole. A spring 162 mounted in a bore in the slide and engaging the bracket 18 at its upper end tends to move the slide downwardly and holds it initially in a position determined by its engagement with a screw 164 in the bracket, this screw extending into a slot 166 (Fig. 11) in the slide. Fastened to the slide 158 by a bolt 168 (Fig. 12) and a nut 170 is a block 172 carrying a pin 174 on which is mounted for swinging movements an upwardly extending pawl 176 having a shoulder 178 arranged to engage the latch 152 underneath. A leaf spring 180 fastened to the block 172 and engaging the pawl 176 holds the pawl normally in a position determined by its engagement with a shoulder 182 (Fig. 13) on the block, in which position the shoulder 178 of the pawl is under the end of the latch 152 as shown in Fig. 11. By the downward movement of the arm 16 the pin 160 is carried into engagement with the insole, as also shown in Fig. 11, and upon further downward movement of the arm 25 the pin and the slide 158 remain stationary as the bracket 18 is carried farther downwardly. This causes the shoulder 178 of the pawl 176 to engage and lift the latch 152, thus releasing the arms 120 which are swung outwardly by their 30 springs 122 as far as permitted by the rod 124 and the screws 128, thus carrying the retarder members 134 outwardly toward the edge of the insole. In response to engagement of the insole with these members they are also swung farther 35 outwardly with their supporting levers 132 relatively to the arms 120 until they are properly positioned adjacent to the edge of the insole to clamp the upper against the wipers when the wipers receive their operative movements. After 40 the latch 152 has been lifted by the pawl 176, an inclined face 184 on the upper end of the pawl is engaged by a pin 186 mounted in a lug 188 on the bracket 18 to swing the pawl about the pin 174 and thus to cause it to release the 45 latch 152. The latch is then returned by the spring plunger 156 to a position where it rests on top of the pin 154, as shown in Fig. 13, ready to be moved farther downwardly into position to hold the pin when the arms 120 are swung inwardly by the operative movements of the side 50 wipers. The block 172 which supports the pawl 176 is vertically adjustable relatively to the slide 158 to vary the time in the downward movement of the arm 16 when the latch 152 is lifted to release the arms 120, a slot 190 (Fig. 13) being 55 provided in a downwardly extending flange on the block to receive the bolt 168 and permit such adjustment of the block. In the use of the construction shown in Figs. 10 to 13 inclusive the 60 screws 128 which cooperate with the rod 124 to determine the positions to which the arms 120 are swung by their springs 122 are preferably 65 adjusted to permit less swinging movements of the arms than in the use of the construction shown in the other figures, as illustrated in Fig. 13, and accordingly the retarder members 134 and their supporting levers 132 must be swung 70 farther relatively to the arms 120 in response to engagement of the insole with these members 75 to cause the members to assume the proper

positions near the edge of the insole, the relation between the members 134 and the presser foot 14 being such as to permit this. It will be understood that, except as noted, the manner of operation of the alternative retarder mechanism shown in Figs. 10 to 13 inclusive is the same as that of the mechanism shown in the other figures. The arms 120 of the alternative mechanism are to all intents and purposes the same as the corresponding arms of the other mechanism, although somewhat differently designed, as are also some other parts of the alternative mechanism.

Having described the invention, what I claim as new and desire to secure by Letters Patent of the United States is:

1. In a lasting machine, end wipers for wiping the margin of an upper inwardly over an insole on a last around an end of the last, side wipers for wiping the margin of the upper inwardly over the insole at the sides of the shoe beyond the end wipers, the end wipers being spaced initially lengthwise of the shoe from the side wipers, and means for swinging all said wipers at substantially the same time inwardly over the shoe bottom about axes extending heightwise of the shoe and located about the portion of the shoe on which the end wipers operate and for also moving the end wipers bodily lengthwise of the shoe toward the side wipers.

2. In a lasting machine, end wipers for wiping the margin of an upper inwardly over an insole on a last around an end of the last, side wipers for wiping the margin of the upper inwardly over the insole at the sides of the shoe beyond the end wipers, the end wipers being spaced initially lengthwise of the shoe from the side wipers, means for swinging the side wipers inwardly over the shoe bottom about different axes extending heightwise of the shoe and spaced apart laterally of the shoe in locations opposite the sides of the portion of the shoe on which the end wipers operate, and means for swinging the end wipers inwardly about a common axis at the end of the shoe at substantially the same time as the side wipers and for also advancing them bodily lengthwise of the shoe substantially into engagement with the side wipers over the shoe bottom.

3. In a lasting machine, toe wipers for wiping the margin of an upper inwardly over an insole on a last around the toe end of the last, side wipers for wiping the margin of the upper inwardly over the insole at the sides of the forepart beyond the toe wipers, the toe wipers being spaced initially lengthwise of the shoe from the side wipers, means for moving the side wipers inwardly over the shoe bottom with components of movement lengthwise of the shoe toward the toe wipers, and means for moving the toe wipers inwardly widthwise of the shoe at substantially the same time as the side wipers and for advancing them lengthwise of the shoe substantially into engagement with the side wipers.

4. In a lasting machine, toe wipers for wiping the margin of an upper inwardly over an insole on a last around the toe end of the last, side wipers for wiping the margin of the upper inwardly over the insole at the sides of the forepart beyond the toe wipers, the toe wipers being spaced initially lengthwise of the shoe from the side wipers, means for swinging the side wipers inwardly over the shoe bottom about axes so located as to cause them to have components of movement lengthwise of the shoe toward the

toe wipers, and means for swinging the toe wipers inwardly and for advancing them bodily lengthwise of the shoe substantially into engagement with the side wipers over the shoe bottom.

5. In a lasting machine, toe wipers for wiping the margin of an upper inwardly over an insole on a last around the toe end of the last, side wipers for wiping the margin of the upper inwardly over the insole at the sides of the forepart beyond the toe wipers, the toe wipers being spaced initially lengthwise of the shoe from the side wipers, and means for moving all said wipers inwardly over the shoe bottom widthwise of the shoe while advancing the toe wipers lengthwise of the shoe toward the side wipers into substantially contiguous relation thereto and for also moving the side wipers lengthwise of the shoe in the same direction as the toe wipers near the end of the wiping operation.

6. In a lasting machine, toe wipers for wiping the margin of an upper inwardly over an insole on a last around the toe end of the last, side wipers for wiping the margin of the upper inwardly over the insole at the sides of the forepart beyond the toe wipers, the toe wipers being spaced initially lengthwise of the shoe from the side wipers, means for swinging the toe wipers inwardly over the shoe bottom and for advancing them bodily lengthwise of the shoe to meet the side wipers, and means for swinging the side wipers inwardly about axes extending heightwise of the shoe at substantially the same time as the toe wipers and for further moving them lengthwise of the shoe with the toe wipers after they are met by the toe wipers near the end of the wiping operation.

7. In a lasting machine, toe wipers for wiping the margin of an upper inwardly over an insole on a last around the toe end of the last, side wipers for wiping the margin of the upper inwardly over the insole at the sides of the forepart beyond the toe wipers, the toe wipers being spaced initially lengthwise of the shoe from the side wipers, means for moving the toe wipers inwardly over the shoe bottom widthwise of the shoe and for advancing them lengthwise of the shoe toward the side wipers, and means for moving the side wipers inwardly over the shoe bottom with components of movement lengthwise of the shoe toward the toe wipers during a portion of the wiping operation and with components of movement in the opposite direction lengthwise of the shoe with the toe wipers near the end of the wiping operation.

8. In a lasting machine, toe wipers for wiping the margin of an upper inwardly over an insole on a last around the toe end of the last, side wipers for wiping the margin of the upper inwardly over the insole at the sides of the forepart beyond the toe wipers, the toe wipers being spaced initially lengthwise of the shoe from the side wipers, means for swinging the toe wipers inwardly over the shoe bottom and for advancing them bodily lengthwise of the shoe to meet the side wipers, and means for moving the side wipers inwardly over the shoe bottom with components of movement lengthwise of the shoe toward the toe wipers and for thereafter moving them bodily lengthwise of the shoe with the toe wipers after they are met by the toe wipers near the end of the wiping operation.

9. In a lasting machine, end wipers for wiping the margin of an upper inwardly over an insole on a last around an end of the last, side wipers for wiping the margin of the upper inwardly over

the insole at the sides of the shoe beyond the end wipers, members associated respectively with the different end wipers and mounted for turning movements about different axes extending heightwise of the shoe to close the end wipers inwardly widthwise of the shoe, wiper carriers supporting the side wipers and movable relatively to the end wipers by the turning of said members, and means for guiding said wiper carriers to determine the paths of movement of the side wipers.

10. In a lasting machine, end wipers for wiping the margin of an upper inwardly over an insole on a last around an end of the last, side wipers for wiping the margin of the upper inwardly over the insole at the sides of the shoe beyond the end wipers, members associated respectively with the different end wipers and mounted for turning movements about axes extending heightwise of the shoe to close the end wipers inwardly widthwise of the shoe, wiper carriers supporting the side wipers and movable bodily by the turning of said members to operate the side wipers, the forces applied by the members to said wiper carriers being directed generally lengthwise of the shoe, and means for guiding the wiper carriers to cause the side wipers to be moved inwardly widthwise of the shoe by the movements of the carriers.

11. In a lasting machine, toe wipers for wiping the margin of an upper inwardly over an insole on a last around the toe end of the last, side wipers for wiping the margin of the upper inwardly over the insole at the sides of the forepart beyond the toe wipers, members associated respectively with the different toe wipers and mounted for turning movements about axes extending heightwise of the shoe to close the toe wipers inwardly widthwise of the shoe, wiper carriers supporting the side wipers and movable bodily by the turning of said members to operate the side wipers, the wiper carriers being pivotally connected to said members for swinging movements laterally of the shoe combined with their bodily movements, and means for thus swinging the carriers in response to the forces applied thereto by said members.

12. In a lasting machine, toe wipers for wiping the margin of an upper inwardly over an insole on a last around the toe end of the last, side wipers for wiping the margin of the upper inwardly over the insole at the sides of the forepart beyond the toe wipers, members associated respectively with the different toe wipers and mounted for turning movements about axes extending heightwise of the shoe to close the toe wipers inwardly widthwise of the shoe, wiper carriers supporting the side wipers and movable relatively to the toe wipers by the turning of said members, said wiper carriers having cam faces thereon, and means for engaging said cam faces to determine the paths of movement of the side wipers.

13. In a lasting machine, toe wipers for wiping the margin of an upper inwardly over an insole on a last around the toe end of the last, side wipers for wiping the margin of the upper inwardly over the insole at the sides of the forepart beyond the toe wipers, members associated respectively with the different toe wipers and mounted for turning movements about axes extending heightwise of the shoe to close the toe wipers inwardly widthwise of the shoe, wiper carriers supporting the side wipers and movable bodily by the turning of said members to operate the side wipers, the forces applied to the carriers by said members being directed generally lengthwise of the shoe and the carriers being connected to said members for swinging

movements laterally of the shoe combined with their bodily movements, and guiding means for thus swinging said wiper carriers to cause the side wipers to be moved inwardly widthwise of the shoe.

14. In a lasting machine, toe wipers for wiping the margin of an upper inwardly over an insole on a last around the toe end of the last, side wipers for wiping the margin of the upper inwardly over the insole at the sides of the forepart beyond the toe wipers, members associated respectively with the different toe wipers and mounted for turning movements about axes extending heightwise of the shoe to close the toe wipers inwardly widthwise of the shoe, links pivotally connected to said members and to the toe wipers for thus closing the toe wipers by said members, and wiper carriers supporting the side wipers and pivotally connected to said members for operating the side wipers also by the turning of said members.

15. In a lasting machine, toe wipers for wiping the margin of an upper inwardly over an insole on a last around the toe end of the last, side wipers for wiping the margin of the upper inwardly over the insole at the sides of the forepart beyond the toe wipers, members associated respectively with the different toe wipers and mounted for turning movements about axes extending heightwise of the shoe to close the toe wipers inwardly widthwise of the shoe, links pivotally connected to said members and to the toe wipers for thus closing the toe wipers by said members, wiper carriers supporting the side wipers and movable bodily by the turning of said members to operate the side wipers, said wiper carriers being pivotally connected to said members for swinging movements laterally of the shoe combined with their bodily movements and having cam faces thereon, and means for engaging said cam faces thus to swing the wiper carriers.

16. In a lasting machine, toe wipers for wiping the margin of an upper inwardly over an insole on a last around the toe end of the last, side wipers for wiping the margin of the upper inwardly over the insole at the sides of the forepart beyond the toe wipers, the toe wipers being spaced initially lengthwise of the shoe from the side wipers, means for advancing the toe wipers bodily lengthwise of the shoe toward the side wipers, members associated respectively with the different toe wipers and mounted for turning movements about axes extending heightwise of the shoe to close the toe wipers inwardly widthwise of the shoe, and means for operating the side wipers by the turning of said members.

17. In a lasting machine, toe wipers for wiping the margin of an upper inwardly over an insole on a last around the toe end of the last, side wipers for wiping the margin of the upper inwardly over the insole at the sides of the forepart beyond the toe wipers, the toe wipers being spaced initially lengthwise of the shoe from the side wipers, means for advancing the toe wipers bodily lengthwise of the shoe toward the side wipers, members associated respectively with the different toe wipers and mounted for turning movements about axes extending heightwise of the shoe to close the toe wipers inwardly widthwise of the shoe, wiper carriers supporting the side wipers and movable by the turning of said members to operate the side wipers, and means for guiding said wiper carriers to deter-

mine the paths of movement of the side wipers.

18. In a lasting machine, toe wipers for wiping the margin of an upper inwardly over an insole on a last around the toe end of the last, side wipers for wiping the margin of the upper inwardly over the insole at the sides of the forepart beyond the toe wipers, the toe wipers being spaced initially lengthwise of the shoe from the side wipers, means for advancing the toe wipers bodily lengthwise of the shoe toward the side wipers, members associated respectively with the different toe wipers and mounted for turning movements about axes extending heightwise of the shoe to close the toe wipers inwardly widthwise of the shoe, wiper carriers supporting the side wipers and movable bodily by the turning of said members to operate the side wipers, the wiper carriers being pivotally connected to said members for swinging movements laterally of the shoe combined with their bodily movements, and means for thus swinging the carriers in response to the forces applied thereto by said members.

19. In a lasting machine, toe wipers for wiping the margin of an upper inwardly over an insole on a last around the toe end of the last, side wipers for wiping the margin of the upper inwardly over the insole at the sides of the forepart beyond the toe wipers, members associated respectively with the different toe wipers and mounted for turning movements about axes extending heightwise of the shoe to close the toe wipers inwardly widthwise of the shoe, and means for moving the side wipers inwardly over the shoe bottom widthwise of the shoe with components of movement lengthwise of the shoe toward the toe end thereof by the turning of said members.

20. In a lasting machine, toe wipers for wiping the margin of an upper inwardly over an insole on a last around the toe end of the last, side wipers for wiping the margin of the upper inwardly over the insole at the sides of the forepart beyond the toe wipers, the toe wipers being spaced initially lengthwise of the shoe from the side wipers, means for moving the toe wipers bodily lengthwise of the shoe toward the side wipers, members associated respectively with the different toe wipers and mounted for turning movements about axes extending heightwise of the shoe to close the toe wipers inwardly widthwise of the shoe, and means for moving the side wipers inwardly over the shoe bottom widthwise of the shoe with components of movement lengthwise of the shoe toward the toe wipers by the turning of said members.

21. In a lasting machine, toe wipers for wiping the margin of an upper inwardly over an insole on a last around the toe end of the last, side wipers for wiping the margin of the upper inwardly over the insole at the sides of the forepart beyond the toe wipers, the toe wipers being spaced initially lengthwise of the shoe from the side wipers, means for moving the toe wipers bodily lengthwise of the shoe toward the side wipers, members associated respectively with the different toe wipers and mounted for turning movements about axes extending heightwise of the shoe to close the toe wipers inwardly widthwise of the shoe, and means for moving the side wipers inwardly over the shoe bottom widthwise of the shoe and for further moving them lengthwise of the shoe in the same direction as the toe wipers near the end of the wiping operation by the turning of said members.

22. In a lasting machine, toe wipers for wiping the margin of an upper inwardly over an insole on a last around the toe end of the last, side wipers for wiping the margin of the upper inwardly over the insole at the sides of the forepart beyond the toe wipers, the toe wipers being spaced initially lengthwise of the shoe from the side wipers, means for moving the toe wipers bodily lengthwise of the shoe toward the side wipers, members associated respectively with the different toe wipers and mounted for turning movements about axes extending heightwise of the shoe to close the toe wipers inwardly widthwise of the shoe, wiper carriers supporting the side wipers and movable by the turning of said members to operate the side wipers, and means for guiding said wiper carriers to cause the side wipers to be moved inwardly over the shoe bottom with components of movement lengthwise of the shoe toward the toe wipers.

23. In a lasting machine, toe wipers for wiping the margin of an upper inwardly over an insole on a last around the toe end of the last, side wipers for wiping the margin of the upper inwardly over the insole at the sides of the forepart beyond the toe wipers, the toe wipers being spaced initially lengthwise of the shoe from the side wipers, means for moving the toe wipers bodily lengthwise of the shoe toward the side wipers, members associated respectively with the different toe wipers and mounted for turning movements about axes extending heightwise of the shoe to close the toe wipers inwardly widthwise of the shoe, wiper carriers supporting the side wipers and movable bodily by the turning of said members to operate the side wipers, said wiper carriers being pivotally connected to said members for swinging movements laterally of the shoe combined with their bodily movements and having cam faces thereon, and means for engaging said cam faces to determine the paths of movement of the side wipers, said cam faces being so formed as to cause the side wipers to be moved inwardly over the shoe bottom with components of movement lengthwise of the shoe toward the toe wipers.

24. In a lasting machine, toe wipers for wiping the margin of an upper inwardly over an insole on a last around the toe end of the last, side wipers for wiping the margin of the upper inwardly over the insole at the sides of the forepart beyond the toe wipers, wiper carriers supporting the side wipers independently of the toe wipers, means for applying to said wiper carriers forces directed generally lengthwise of the shoe toward its heel end to operate the side wipers, and means for guiding said wiper carriers to cause the side wipers to be moved inwardly widthwise of the shoe by the forces thus applied to the carriers.

25. In a lasting machine, toe wipers for wiping the margin of an upper inwardly over an insole on a last around the toe end of the last, side wipers for wiping the margin of the upper inwardly over the insole at the sides of the forepart beyond the toe wipers, wiper carriers supporting the side wipers independently of the toe wipers, members movable to apply to said wiper carriers forces directed generally lengthwise of the shoe toward its heel end to operate the side wipers, the wiper carriers being pivotally connected to said members for swinging movements widthwise of the shoe, and guiding means for thus swinging the wiper carriers to move the side wipers inwardly over the shoe bottom in re-

sponse to the forces applied to the carriers by said members.

26. In a lasting machine, toe wipers for wiping the margin of an upper inwardly over an insole on a last around the toe end of the last, side wipers for wiping the margin of the upper inwardly over the insole at the sides of the forepart beyond the toe wipers, wiper carriers supporting the side wipers independently of the toe wipers, members movable to apply to said wiper carriers forces directed generally lengthwise of the shoe to operate the side wipers, the wiper carriers being pivotally connected to said members for swinging movements widthwise of the shoe, said wiper carriers having cam faces thereon, means for engaging said cam faces to swing the wiper carriers and thus to impart inward wiping movements to the side wipers in response to the forces applied to the carriers by said members, and spring means tending to swing the wiper carriers outwardly and against the resistance of which they are thus movable to operate the side wipers.

27. In a lasting machine, toe wipers for wiping the margin of an upper inwardly over an insole on a last all around the toe end of the last, side wipers for wiping the margin of the upper inwardly over the insole from the ends of the toe wipers along the sides of the ball portion of the shoe, the side wipers being spaced initially lengthwise of the shoe from the toe wipers, means for moving the toe wipers and the side wipers inwardly over the shoe bottom at substantially the same time while moving the toe wipers lengthwise of the shoe toward the side wipers, the side wipers being pivotally supported for swinging movements heightwise of the shoe relatively to the toe wipers about axes extending lengthwise of the shoe, and springs against the resistance of which the side wipers are thus movable heightwise of the shoe in response to deflecting action of the upper thereon at the edge of the shoe bottom.

28. In a lasting machine, toe wipers for wiping the margin of an upper inwardly over an insole on a last all around the toe end of the last, side wipers for wiping the margin of the upper inwardly over the insole from the ends of the toe wipers along the sides of the ball portion of the shoe, means for moving the toe wipers and the side wipers inwardly over the shoe bottom at substantially the same time, the side wipers being pivotally supported for swinging movements heightwise of the shoe relatively to the toe wipers about axes extending lengthwise of the shoe, and springs against the resistance of which the side wipers are thus movable heightwise of the shoe in response to deflecting action of the upper thereon at the edge of the shoe bottom, the side wipers including upper-engaging plates resiliently flexible heightwise of the shoe for better conformity to the lengthwise contour of the bottom of the ball portion of the shoe.

29. In a lasting machine, toe-lasting means including wipers movable to wipe the margin of an upper inwardly over an insole on a last around the toe end of the last, a shoe-controlling device movable in a direction heightwise of the shoe and provided with a presser foot for engaging the insole to move the shoe in that direction relatively to the toe-lasting means before the margin of the upper is wiped inwardly by the toe wipers, side wipers movable to wipe the margin of the upper inwardly over the insole at the sides of the ball portion of the shoe after such movement

of the shoe, and members carried by said shoe-controlling device for pressing the marginal portion of the upper against the side wipers to control it as it is wiped inwardly over the insole.

30. In a lasting machine, toe-lasting means including wipers movable to wipe the margin of an upper inwardly over an insole on a last around the toe end of the last, a shoe-controlling device movable in a direction heightwise of the shoe to move the shoe in that direction relatively to the toe-lasting means by engagement with the insole before the margin of the upper is wiped inwardly by the toe wipers, side wipers movable to wipe the margin of the upper inwardly over the insole at the sides of the ball portion of the shoe after such movement of the shoe, and members carried by said shoe-controlling device for pressing the marginal portion of the upper against the side wipers to control it as it is wiped inwardly over the insole, said members being movable outwardly over the insole into positions for thus controlling the upper and movable thereafter inwardly over the insole by the side wipers.

31. In a lasting machine, toe-lasting means including wipers movable to wipe the margin of an upper inwardly over an insole on a last around the toe end of the last, a shoe-controlling device movable in a direction heightwise of the shoe to move the shoe in that direction relatively to the toe-lasting means by engagement with the insole before the margin of the upper is wiped inwardly by the toe wipers, side wipers movable to wipe the margin of the upper inwardly over the insole at the sides of the ball portion of the shoe after such movement of the shoe, and members carried by said shoe-controlling device for pressing the margin of the insole on the bottom of the last at the sides of the ball portion of the shoe and for pressing the marginal portion of the upper against the side wipers to control it as it is wiped inwardly over the insole, said members being movable outwardly over the insole toward the opposite side edges thereof in response to engagement of the insole therewith and being movable thereafter inwardly over the insole by the side wipers.

32. In a lasting machine, wipers movable to wipe the margin of an upper inwardly over an insole on a last at the opposite sides of the forepart, a presser foot for engaging the forepart of the insole to control the shoe in the lasting operation, a presser foot carrier movable heightwise of the shoe to carry the presser foot into engagement with the insole, and members supported by said presser foot carrier for pressing the marginal portion of the forepart of the upper against said wipers to control it as it is wiped inwardly over the insole, said members being movable inwardly over the insole by the wipers.

33. In a lasting machine, wipers movable to wipe the margin of an upper inwardly over an insole on a last at the opposite sides of the forepart, a presser foot for engaging the forepart of the insole to control the shoe in the lasting operation, a presser foot carrier movable heightwise of the shoe to carry the presser foot into engagement with the insole, and members supported by said presser foot carrier for pressing the marginal portion of the forepart of the upper against said wipers to control it as it is wiped inwardly over the insole, said members being arranged to engage the insole before the presser foot and being movable outwardly toward the opposite side edges of the insole in response to the engagement of the insole therewith, the members being there-

after movable inwardly over the insole by the wipers.

34. In a lasting machine, toe-lasting means including wipers movable to wipe the margin of an upper inwardly over an insole on a last around the toe end of the last, a shoe-controlling device movable in a direction heightwise of the shoe and having a presser foot for engaging the insole to move the shoe in that direction relatively to the toe-lasting means before the margin of the upper is wiped inwardly by the toe wipers, side wipers movable to wipe the margin of the upper inwardly over the insole at the sides of the forepart beyond the toe wipers after such movement of the shoe, and members carried by said shoe-controlling device for tipping the shoe laterally into proper relation to the several wipers if it is not already in that relation by engagement with the insole before the insole is engaged by said presser foot, said members being thereafter movable inwardly over the insole by the side wipers while pressing the marginal portion of the upper against those wipers.

35. In a lasting machine, toe-lasting means including wipers movable to wipe the margin of an upper inwardly over an insole on a last around the toe end of the last, a shoe-controlling device movable in a direction heightwise of the shoe and having a presser foot for engaging the insole to move the shoe in that direction relatively to the toe-lasting means before the margin of the upper is wiped inwardly by the toe wipers, side wipers movable to wipe the margin of the upper inwardly over the insole at the sides of the forepart beyond the toe wipers after such movement of the shoe, and members carried by said shoe-controlling device for pressing the marginal portion of the upper against the side wipers to control it as it is wiped inwardly over the insole, said members being movable outwardly over the insole toward the side wipers in response to engagement of the insole therewith before it is engaged by said presser foot and being arranged to tip the shoe laterally by such engagement with the insole to position it in proper relation to the several wipers if it is not already in that relation, the members being thereafter movable inwardly over the insole by the side wipers.

36. In a lasting machine, wipers movable to wipe the margin of an upper inwardly over an insole on a last at the opposite sides of the forepart, a presser foot for engaging the insole to control the shoe in the lasting operation, a presser-foot carrier movable heightwise of the shoe to carry the presser foot into engagement with the insole, and members supported by said presser-foot carrier for tipping the shoe laterally into proper relation to the wipers if it is not already in that relation by engagement with the forepart of the insole before the insole is engaged by said presser foot, said members being thereafter movable inwardly over the insole by the side wipers while pressing the marginal portion of the upper against those wipers.

37. In a lasting machine, means movable to lay the margin of an upper inwardly over an insole on a last, a member arranged to press the marginal portion of the upper against said overlaying means to control it as it is laid inwardly over the insole, said member being movable outwardly over the insole into position thus to control the upper and movable thereafter inwardly over the insole by the overlaying means, and a support for said member relatively to which it is thus outwardly movable, said support being movable with said

member when the member is moved inwardly over the insole.

38. In a lasting machine, means movable to lay the margin of an upper inwardly over an insole on a last, a member arranged to press the marginal portion of the upper against said overlaying means to control it as it is laid inwardly over the insole, said member being movable outwardly over the insole into position thus to control the upper and movable thereafter inwardly over the insole by the overlaying means, an arm supporting said member and relatively to which the member is thus outwardly movable, said arm being mounted to swing about an axis, and a spring against the resistance of which the arm is thus movable about its axis by said member in response to pressure of the overlaying means on the member in laying the upper inwardly over the insole.

39. In a lasting machine, means movable to lay the margin of an upper inwardly over an insole on a last, a member arranged to press the marginal portion of the upper against said overlaying means to control it as it is laid inwardly over the insole, said member being movable outwardly over the insole into position thus to control the upper and movable thereafter inwardly over the insole by the overlaying means, a support for said member relatively to which it is thus outwardly movable, and means for preventing the member from being moved reversely in an inward direction relatively to said support as the upper is laid inwardly over the insole, the support being movable with said member when the member is moved inwardly over the insole by the overlaying means.

40. In a lasting machine, means movable to lay the margin of an upper inwardly over an insole on a last, a member arranged to press the marginal portion of the upper against said overlaying means to control it as it is laid inwardly over the insole, said member being arranged to swing outwardly over the insole into position thus to control the upper and being movable thereafter inwardly over the insole by the overlaying means, an arm supporting said member and relatively to which the member is thus outwardly movable, means for preventing said member from being swung reversely in an inward direction relatively to said arm as the upper is laid inwardly over the insole, the arm being mounted to swing about an axis and being thus movable by said member when the member is moved inwardly over the insole by the overlaying means, and a spring against the resistance of which the arm is thus movable.

41. In a lasting machine, means movable to lay the margin of an upper inwardly over an insole on a last, a member arranged to press the marginal portion of the upper against said overlaying means to control it as it is laid inwardly over the insole, said member being movable outwardly over the insole into position thus to control the upper and movable thereafter inwardly over the insole by the overlaying means, a support for said member relatively to which it is thus outwardly movable, said support being mounted to move in the same direction as said member when the member is moved inwardly over the insole by the overlaying means, means for preventing the member from being moved in an inward direction relatively to said support and for thereby causing the support to be moved by said member in the overlaying operation, and a spring against the resistance of which the support is thus movable.

42. In a lasting machine, means movable to lay

the margin of an upper inwardly over an insole on a last, and a member arranged to press the marginal portion of the upper against said overlaying means to control it as it is laid inwardly over the insole, said member being movable outwardly over the insole into position thus to control the upper in response to pressure of the insole thereon and movable thereafter inwardly over the insole by the overlaying means.

43. In a lasting machine, means movable to lay the margin of an upper inwardly over an insole on a last, a member arranged to press the marginal portion of the upper against said overlaying means to control it as it is laid inwardly over the insole, said member being movable outwardly over the insole into position thus to control the upper in response to pressure of the insole thereon and movable thereafter inwardly over the insole by the overlaying means, and a support for said member relatively to which it is thus outwardly movable, said member and its support being movable as a unit as the member is moved inwardly over the insole by the overlaying means.

44. In a lasting machine, means movable to lay the margin of an upper inwardly over an insole on a last, a member arranged to press the marginal portion of the upper against said overlaying means to control it as it is laid inwardly over the insole, said member being movable outwardly over the insole into position thus to control the upper in response to pressure of the insole thereon and movable thereafter inwardly over the insole by the overlaying means, a spring against the resistance of which the member is thus outwardly movable, a support for said member relatively to which it is thus movable, the support being movable by said member when the member is moved inwardly over the insole, and a spring for yieldingly resisting such movement of the support.

45. In a lasting machine, wipers movable to wipe the margin of an upper inwardly over an insole on a last at the opposite sides of the last, members arranged to press the marginal portion of the upper against said wipers to control it as it is wiped inwardly over the insole, said members being movable outwardly over the insole into positions thus to control the upper and movable thereafter inwardly over the insole by the wipers, supports for said members relatively to which they are thus outwardly movable, said supports being mounted for movements widthwise of the last, and means to cause said members and their supports to move as units widthwise of the last when the members are moved inwardly over the insole by the wipers.

46. In a lasting machine, wipers movable to wipe the margin of an upper inwardly over an insole on a last at the opposite sides of the last, members arranged to press the marginal portion of the upper against said wipers to control it as it is wiped inwardly over the insole, said members being movable outwardly over the insole into positions thus to control the upper and movable thereafter inwardly over the insole by the wipers, supports for said members relatively to which they are thus outwardly movable, said supports being mounted for movements widthwise of the last, and spring means against the resistance of which said supports are thus movable with said members when the members are moved inwardly over the insole by the wipers.

47. In a lasting machine, wipers movable to wipe the margin of an upper inwardly over an insole on a last at the opposite sides of the last,

members arranged to press the marginal portion of the upper against said wipers to control it as it is wiped inwardly over the insole, said members being movable outwardly over the insole into positions thus to control the upper and movable thereafter inwardly over the insole by the wipers, supports for said members relatively to which they are thus outwardly movable, said supports being mounted for movements widthwise of the last, means for preventing said members from being moved reversely inward over the insole relatively to their supports and for thereby causing said supports to move with the members when the members are moved inwardly by the wipers, and spring means against the resistance of which the supports are thus movable.

48. In a lasting machine, wipers movable to wipe the margin of an upper inwardly over an insole on a last at the opposite sides of the last, members arranged to press the marginal portion of the upper against said wipers to control it as it is wiped inwardly over the insole, said members being mounted to swing outwardly over the insole into positions thus to control the upper and being movable thereafter inwardly over the insole by the wipers, arms supporting said members and relatively to which they are thus outwardly movable, said arms being mounted to swing widthwise of the last, means controlled by the wipers for preventing the members from being swung reversely inward over the insole relatively to said arms and for thereby causing the arms to be swung by the members as the members are moved inwardly over the insole by the wipers, and spring means for yieldingly resisting such swinging of the arms.

49. In a lasting machine, wipers movable to wipe the margin of an upper inwardly over an insole on a last at the opposite sides of the last, devices arranged to press the marginal portion of the upper against said wipers to control it as it is wiped inwardly over the insole, said devices being mounted to swing outwardly over the insole into positions thus to control the upper and being movable thereafter inwardly over the insole by the wipers, supports for said devices relatively to which they are thus outwardly movable, said supports being mounted for movements widthwise of the last, said devices having outwardly extending arms arranged to be controlled by the wipers to prevent the devices from being swung reversely inward over the insole relatively to their supports and thereby to cause said supports to move with the devices when the latter are moved inwardly over the insole by the wipers, and spring means against the resistance of which the supports are thus movable.

50. In a lasting machine, wipers movable to wipe the margin of an upper inwardly over an insole on a last at the opposite sides of the last, and members arranged to press the marginal portion of the upper against said wipers to control it as it is wiped inwardly over the insole, said members being movable outwardly over the insole toward the wipers in response to pressure of the insole thereon prior to the wiping of the upper over the insole and movable thereafter inwardly over the insole by the wipers.

51. In a lasting machine, wipers movable to wipe the margin of an upper inwardly over an insole on a last at the opposite sides of the last, members arranged to press the marginal portion of the upper against said wipers to control it as it is wiped inwardly over the insole, and

means supporting said members for swinging movements outwardly over the insole toward the wipers in response to pressure of the insole thereon, the members being movable thereafter inwardly over the insole by the wipers.

52. In a lasting machine, wipers movable to wipe the margin of an upper inwardly over an insole on a last at the opposite sides of the last, members arranged to press the marginal portion of the upper against said wipers to control it as it is wiped inwardly over the insole, and spring means tending to move said members toward each other widthwise of the shoe and against the resistance of which they are movable outwardly over the insole toward the wipers in response to pressure of the insole upon them, the members being movable thereafter inwardly over the insole by the wipers.

53. In a lasting machine, wipers movable to wipe the margin of an upper inwardly over an insole on a last at the opposite sides of the last, members arranged to press the marginal portion of the upper against said wipers to control it as it is wiped inwardly over the insole, and a support for said members movable to carry them heightwise of the last into engagement with the insole, the members being movable outwardly over the insole toward the wipers in response to such engagement with the insole and movable thereafter inwardly over the insole by the pressure of the wipers thereon.

54. In a lasting machine, wipers movable to wipe the margin of an upper inwardly over an insole on a last at the opposite sides of the last, members arranged to press the marginal portion of the upper against said wipers to control it as it is wiped inwardly over the insole, said members being movable outwardly over the insole toward the wipers in response to pressure of the insole thereon and movable thereafter inwardly over the insole by the wipers, and supports for said members relatively to which the members are thus outwardly movable, said supports being movable with the members when the latter are moved inwardly over the insole by the wipers.

55. In a lasting machine, wipers movable to wipe the margin of an upper inwardly over an insole on a last at the opposite sides of the last, members arranged to press the marginal portion of the upper against said wipers to control it as it is wiped inwardly over the insole, said members being arranged to swing outwardly over the insole toward the wipers in response to pressure of the insole thereon and being movable thereafter inwardly over the insole by the wipers, arms supporting said members and relatively to which they are thus outwardly movable, said arms being mounted for swinging movements widthwise of the last, and spring means against the resistance of which the arms are movable with said members as the members are moved inwardly over the insole by the wipers.

56. In a lasting machine, means movable to lay the margin of an upper inwardly over an insole on a last, a member arranged to press the marginal portion of the upper against said overlaying means to control it as it is laid inwardly over the insole, said member being movable inwardly over the insole by the overlaying means, a device for retaining said member initially in an inwardly retracted position, means controlled by the shoe for causing said device to release the member, and means for moving the member outwardly over the insole when it is thus released.

57. In a lasting machine, means movable to lay the margin of an upper inwardly over an insole on a last, a member arranged to press the marginal portion of the upper against said overlaying means to control it as it is laid inwardly over the insole, said member being movable inwardly over the insole by the overlaying means, a spring for moving said member outwardly over the insole and against the resistance of which it is thus movable inwardly by the overlaying means, a latch arranged to retain the member initially in an inwardly retracted position, and means controlled by the shoe for operating said latch to release the member.

58. In a lasting machine, means movable to lay the margin of an upper inwardly over an insole on a last, a member arranged to press the marginal portion of the upper against said overlaying means to control it as it is laid inwardly over the insole, said member being movable inwardly over the insole by the overlaying means, a spring for moving said member outwardly over the insole and against the resistance of which it is thus movable inwardly by the overlaying means, a device for retaining the member initially in an inwardly retracted position, and means arranged to be engaged by the insole to cause said device to release the member.

59. In a lasting machine, means movable to lay the margin of an upper inwardly over an insole on a last, a member arranged to press the marginal portion of the upper against said overlaying means to control it as it is laid inwardly over the insole, said member being movable inwardly over the insole by the overlaying means, a spring against the resistance of which the member is thus movable inwardly, a retaining device arranged to prevent outward return movement of the member, and means arranged to be controlled by engagement with the next shoe presented to the machine to cause said retaining device to release the member.

60. In a lasting machine, means movable to lay the margin of an upper inwardly over an insole on a last, a member arranged to press the marginal portion of the upper against said overlaying means to control it as it is laid inwardly over the insole, said member being movable outwardly over the insole into position thus to control the upper and movable thereafter inwardly over the insole by the overlaying means, a support for said member relatively to which it is thus part way outwardly movable, said support being movable with said member when the member is moved inwardly over the insole, a spring against the resistance of which the support is thus movable, and means for preventing return movement of said support when the overlaying means is retracted from over the shoe.

61. In a lasting machine, means movable to lay the margin of an upper inwardly over an insole on a last, a member arranged to press the marginal portion of the upper against said overlaying means to control it as it is laid inwardly over the insole, said member being movable outwardly over the insole into position thus to control the upper and movable thereafter inwardly over the insole by the overlaying means, a support for said member relatively to which it is thus part way outwardly movable, said support being movable with said member when the member is moved inwardly over the insole, a spring against the resistance of which the support is thus movable, a device for holding said support against return movement when the overlaying

means is retracted from over the shoe, and means arranged to be controlled by the next shoe presented to the machine to cause said device to release the support.

62. In a lasting machine, wipers movable to wipe the margin of an upper inwardly over an insole on a last at the opposite sides of the last, members arranged to press the marginal portion of the upper against said wipers to control it as it is wiped inwardly over the insole, said members being movable inwardly over the insole by the wipers, means for retaining said members initially in inwardly retracted positions widthwise of the shoe, mechanism arranged to be controlled by the shoe to cause said retaining means to release the members, and spring means for moving the members outwardly toward the edge of the insole when they are thus released.

63. In a lasting machine, wipers movable to wipe the margin of an upper inwardly over an insole on a last at the opposite sides of the last, members arranged to press the marginal portion of the upper against said wipers to control it as it is wiped inwardly over the insole, said members being movable inwardly over the insole by the wipers, spring means against the resistance of which the members are thus movable inwardly, retaining means for automatically preventing outward return movements of the members when the wipers are retracted from over the shoe, and mechanism arranged to be controlled by the next shoe presented to the machine to cause said retaining means to release the members.

64. In a lasting machine, wipers movable to wipe the margin of an upper inwardly over an insole on a last at the opposite sides of the last, members arranged to press the marginal portion of the upper against said wipers to control it as it is wiped inwardly over the insole, said members being movable inwardly over the insole by the wipers, spring means against the resistance of which the members are thus movable inwardly, latch mechanism for automatically preventing outward return movements of the members when the wipers are retracted from over the shoe, and a device arranged to be engaged by the insole of the next shoe presented to the machine to cause said latch mechanism to release the members.

65. In a lasting machine, wipers movable to wipe the margin of an upper inwardly over an insole on a last at the opposite sides of the last, members arranged to press the marginal portion of the upper against said wipers to control it as it is wiped inwardly over the insole, said members being movable inwardly over the insole by the wipers, means for retaining said members initially in inwardly retracted positions widthwise of the shoe, a support for said members movable heightwise of the shoe to carry them toward the insole, automatic means for releasing the members in response to the movement of said support, and means for moving the members outwardly toward the edge of the insole when they are thus released.

66. In a lasting machine, wipers movable to wipe the margin of an upper inwardly over an insole on a last at the opposite sides of the last, members arranged to press the margin portion of the upper against said wipers to control it as it is wiped inwardly over the insole, said members being movable inwardly over the insole by the wipers, spring means against the resistance of which the members are thus movable inwardly, retaining means for automatically preventing

outward return movements of the members when the wipers are retracted from over the shoe, a support for the members movable heightwise of the next shoe presented to the machine to carry them toward the bottom of that shoe, and mechanism carried by said support and arranged to be engaged by that shoe to cause said retaining means to release the members.

67. In a lasting machine, wipers movable to wipe the margin of an upper inwardly over an insole on a last at the opposite sides of the last, members arranged to press the marginal portion of the upper against said wipers to control it as it is wiped inwardly over the insole, said members being movable outwardly over the insole into positions thus to control the upper and movable thereafter inwardly over the insole by the wipers, supports for said members relatively to which they are thus part way outwardly movable, said supports being mounted for movements widthwise of the last, spring means against the resistance of which said supports are thus movable with said members when the members are moved inwardly over the insole by the wipers, retaining means for preventing return movements of the supports when the wipers are retracted from over the shoe, and automatic means to cause said retaining means to release the support in the use of the machine to last the next shoe.

68. In a lasting machine, wipers movable to wipe the margin of an upper inwardly over an insole on a last at the opposite sides of the last, members arranged to press the marginal portion of the upper against said wipers to control it as it is wiped inwardly over the insole, said members being movable outwardly over the insole into positions thus to control the upper and movable thereafter inwardly over the insole by the wipers, arms supporting said members and relatively to which they are thus part way outwardly movable, said arms being mounted to swing widthwise of the shoe and being movable about their axes each in one direction as said members are moved inwardly by the wipers, spring means against the resistance of which the arms are thus movable, mechanism for preventing return movements of the arms when the wipers are retracted from over the shoe, and means arranged to be controlled by the next shoe presented to the machine to cause said mechanism to release the arms.

69. In a lasting machine, means movable to lay the margin of an upper inwardly over an insole on a last, a member arranged to be positioned in the path of inward movement of said overlaying means to press the margin of the insole on the bottom of the last before the upper is laid inwardly over it, said member being movable inwardly over the insole by pressure of the margin of the upper against it, and means for relieving the pressure of said member on the insole while still maintaining it in the path of the overlaying means as it is thus moved inwardly.

70. In a lasting machine, means movable to lay the margin of an upper inwardly over an insole on a last, a member arranged to be positioned in the path of inward movement of said overlaying means to press the margin of the insole on the bottom of the last before the upper is laid inwardly over it, said member being movable inwardly over the insole by pressure of the margin of the upper against it, and means to cause said member to move heightwise of the last in a direction away from the insole substantially at the beginning of its inward movement

over the insole while still maintaining it in the path of the overlaying means.

71. In a lasting machine, means movable to lay the margin of an upper inwardly over an insole on a last, said overlaying means being arranged to be deflected heightwise of the last by engagement of the upper therewith at the edge of the insole, a member arranged to be positioned in the path of inward movement of said overlaying means to press the margin of the insole on the bottom of the last, and means for moving said member heightwise of the last in a direction away from the insole by the deflection of the overlaying means heightwise of the last.

72. In a lasting machine, wiping means movable to wipe the margin of an upper inwardly over an insole on a last, a member arranged to press the margin of the insole on the bottom of the last and also to press the upper against said wiping means to control the upper as it is wiped inwardly over the insole, said member being movable inwardly over the insole by the wiping means, and means for moving said member heightwise of the last in a direction away from the insole substantially at the beginning of its inward movement over the insole while still maintaining it in position to press the upper against the wiping means.

73. In a lasting machine, wiping means movable to wipe the margin of an upper inwardly over an insole on a last, said wiping means being arranged to be deflected heightwise of the last by engagement of the upper therewith at the edge of the insole, and a member arranged to press the margin of the insole on the bottom of the last and also to press the upper against said wiping means to control the upper as it is wiped inwardly over the insole, said member being movable inwardly over the insole by the wiping means and being also movable heightwise of the last to relieve its pressure on the insole by the deflection of the wiping means heightwise of the last.

74. In a lasting machine, wiping means movable to wipe the margin of an upper inwardly over an insole on a last, said wiping means being arranged to be deflected heightwise of the last by engagement of the upper therewith at the edge of the insole, a member arranged to press the margin of the insole on the bottom of the last and also to press the upper against said wiping means to control the upper as it is wiped inwardly over the insole, said member being movable inwardly over the insole by the wiping means, and means associated with said member arranged to be controlled by the wiping means to relieve the pressure of the member on the insole as the wiping means is deflected heightwise of the last by the upper.

75. In a lasting machine, wipers movable to wipe the margin of an upper inwardly over an insole on a last at the opposite sides of the last, members arranged to be positioned in the paths of inward movement of said wipers to press the margin of the insole on the bottom of the last, said members being movable inwardly over the insole by the wipers while pressing the margin of the upper against the wipers, and means for relieving the pressure of said members on the insole substantially at the beginning of their inward movements over the insole while still maintaining them in positions to press the upper against the wipers.

76. In a lasting machine, wipers movable to wipe the margin of an upper inwardly over an insole on a last at the opposite sides of the last,

members arranged to be positioned in the paths of inward movement of said wipers to press the margin of the insole on the bottom of the last, said members being movable inwardly over the insole by the wipers while pressing the margin of the upper against the wipers, and means controlled by the wipers for moving said members heightwise of the last in a direction away from the insole while still maintaining them in positions to press the upper against the wipers.

77. In a lasting machine, wipers movable to wipe the margin of an upper inwardly over an insole on a last at the opposite sides of the last, said wipers being arranged to be deflected heightwise of the last by engagement of the upper therewith at the edge of the insole, members arranged to be positioned in the paths of inward movement of the wipers to press the margin of the insole on the bottom of the last, and means to cause the wipers as they are deflected heightwise of the last to move said members in the same direction and thereby to relieve the pressure of the members on the insole.

78. In a lasting machine, wipers movable to wipe the margin of an upper inwardly over an insole on a last at the opposite sides of the last, said wipers being arranged to be deflected heightwise of the last by engagement of the upper therewith at the edge of the insole, and devices arranged to be positioned in the paths of inward movement of the wipers to press the margin of the insole on the bottom of the last, said devices having portions arranged to extend outwardly over the wipers to cause the wipers as they are deflected heightwise of the last to move the devices in the same direction.

79. In a lasting machine, means movable to lay the margin of an upper inwardly over an insole on a last, a member arranged to be positioned in the path of inward movement of said overlaying means to press the margin of the insole on the bottom of the last before the upper is laid inwardly over it, said member being movable inwardly over the insole by the overlaying means, a spring for yieldingly resisting such inward movement of the member and for thereafter moving it outwardly over the insole with the overlaying means, and means for moving said member heightwise of the last away from the insole and for thereafter maintaining it far enough from the insole to prevent it from displacing the margin of the upper in its outward movement.

80. In a lasting machine, means movable to lay the margin of an upper inwardly over an insole on a last, said overlaying means being arranged to be deflected heightwise of the last by engagement of the upper therewith at the edge of the insole, a member arranged to be positioned in the path of inward movement of said overlaying means to press the margin of the insole on the bottom of the last before the upper is laid inwardly over it, said member being movable inwardly over the insole by the overlaying means and movable thereafter outwardly over the insole with the overlaying means, and means for moving said member heightwise of the last away from the insole by the deflection of the overlaying means heightwise of the last and for thereafter maintaining it far enough from the insole to prevent it from displacing the margin of the upper in its outward movement.

81. In a lasting machine, wiping means movable to wipe the margin of an upper inwardly

over an insole on a last, a member arranged to press the margin of the insole on the bottom of the last and also to press the upper against said wiping means to control the upper as it is wiped inwardly over the insole, said member being movable inwardly over the insole by the wiping means, a spring for yieldingly resisting such inward movement of the member and for thereafter moving it outwardly over the insole with the wiping means when the latter is retracted from over the shoe bottom, and means for moving said member heightwise of the last away from the insole substantially at the beginning of its inward movement and for thereafter maintaining it far enough from the insole to prevent it from displacing the margin of the upper in its outward movement.

82. In a lasting machine, wipers movable to

wipe the margin of an upper inwardly over an insole on a last at the opposite sides of the last, members arranged to be positioned in the paths of inward movement of said wipers to press the margin of the insole on the bottom of the last and also to press the margin of the upper against the wipers to control it in the wiping operation, said members being movable inwardly over the insole by the wipers and movable thereafter outwardly over the insole with the wipers when they are retracted from over the shoe bottom, and means controlled by the wipers for moving said members heightwise of the last away from the insole and for maintaining them far enough from the insole to prevent them from displacing the margin of the upper in their outward movements.

LLOYD G. MILLER.
